W. G. KING ET AL

LATH BLIND

Filed May 10, 1924

FIG.1. FIG.2. FIG.3.

FIG.2. FIG.3.

FIG. 4.

UNITED STATES PATENT OFFICE.

WALTER GRANT KING AND FARNHAM EDWARD MAYNARD, OF BRISBANE, QUEENSLAND, AUSTRALIA.

LATH BLIND.

Application filed May 10, 1924. Serial No. 712,370.

To all whom it may concern:

Be it known that we, WALTER GRANT KING and FARNHAM EDWARD MAYNARD, subjects of the King of Great Britain, residing at Brisbane, Queensland, Australia, have invented certain new and useful Improvements in Lath Blinds, of which the following is a specification.

Lath blinds as generally constructed are made of laths woven or connected together by means of twine, string, cord, or wire. The weather generally affects the twine, string, or cord, and causes it to rot and so destroy the blind; on the other hand, the vibration of the blind and the action of rolling and unrolling, when woven with wire, is such that the particles of which the wire is composed gradually become disintegrated and the wire eventually breaks. The laths have also been connected by means of wire links but the formation and arrangement is such that in many cases the laths are weakened, while the link is expensive to make and assemble. The object of this invention is the production of a blind which, while comparatively inexpensive, is practically everlasting, and the arrangement is such that it can be rolled up into small space.

In carrying out our invention, we use laths of the desired length, thickness, and width, of any suitable material. These laths are linked together by means of wire links, which interlace one with the other, and which securely grip the laths.

In order that the invention may be better understood, we will now describe it with the aid of the accompanying drawings, in which—

Fig. 1 is a perspective view of a link and portions of two links, the lath being shown in shadow.

Fig. 2 is an end elevation.

Figs. 3 and 4 are part end elevations of modifications.

The links A are made of wire of suitable metal and gauge. The wire is formed into a loop with two legs B and a straight or

arched connecting portion C. The legs B are bent so that they enfold the lath D, 50 the portions E of the legs being passed on the other side of the lath D and then round the corner of the connecting portion C and legs B, which extend beyond the lath D for that purpose, the ends F of the wire being bent round so as to encircle or partially encircle the legs B of the loop, and, if desired, over the edge of the lath D so as to maintain the connecting or intermediate portion C slightly spaced from the top edge 60 of the lath which is engaged by the loops and consequently permit of the laths relatively free swinging movement and being readily rolled into a compact roll when desired. The legs B may be formed as shown 65 in detail views, Figs. 1 and 2, that is kinked so that the portion C is in alignment with the centre line of the edge of the lath D, or to either side thereof, as shown in Figs. 3 or 4.

In constructing blinds with the links as described, the ends F of the legs B would be threaded between the legs B of the adjacent link so that the bend G would engage the portion C.

The links are pressed well against the lath so as to prevent them moving laterally.

Although this invention is more particularly applicable to the construction of lath blinds, it is obvious that the laths, when so joined, may be used for a variety of purposes, such as mats, packing cases, bush house covers, and so on.

Having now particularly described and ascertained the nature of our said invention and in what manner the same is to be performed, we declare that what we claim is—

In a device of the character described, a plurality of laths and a plurality of links 90 engaging the laths and interengaged with each other, each of said links being formed from a single strand of wire and including an intermediate portion, converging loops continuing therefrom and embracing a lath 95 and also loosely engaged with the intermedi-

ate portion of the adjacent link and anchoring eyelets at the terminals of the wire encircling the portions of the loops adjoining the intermediate portion so as to maintain the latter slightly spaced from the top edge of the engaged lath to permit of the laths being readily rolled into a compact roll when desired.

In testimony whereof we affix our signatures in presence of two witnesses.

WALTER GRANT KING.
FARNHAM EDWARD MAYNARD.

Witnesses:

MABEL C. LOW,
ISABEL BURNS.
